UNITED STATES PATENT OFFICE.

DANIEL N. HYMAN, OF BUFFALO, NEW YORK, ASSIGNOR OF ONE-HALF TO EUGENE WARNER
AND ONE-HALF TO MILLICENT HYMAN, BOTH OF BUFFALO, NEW YORK.

DESIGN FOR A PIPE.

No. 39,788.

Specification for Design.

Patented Jan. 26, 1909.

Application filed September 4, 1908. Serial No. 451,759. Term of patent 7 years.

To all whom it may concern:

Be it known that I, DANIEL N. HYMAN, a citizen of the United States, residing at Buffalo, in the county of Erie and State of New York, have invented a new, original, and ornamental Design for Pipes, of which the following is a specification.

In the accompanying drawing forming

part of this specification, the figure is a side elevation of a pipe embodying the design.

I claim:

The ornamental design for a pipe as shown.

DANIEL N. HYMAN.
